UNITED STATES PATENT OFFICE.

CHARLES H. CHAPMAN, OF GROTON, MASSACHUSETTS.

SPINNING RING AND TRAVELER.

SPECIFICATION forming part of Letters Patent No. 473,824, dated April 26, 1892.

Application filed May 2, 1891. Serial No. 391,389. (No model.)

To all whom it may concern:

Be it known that I, CHARLES H. CHAPMAN, a citizen of the United States, residing at Groton, in the county of Middlesex and State 5 of Massachusetts, have invented a certain new and useful Improvement in Spinning Rings and Travelers, of which the following is a full, clear, and exact description.

This invention relates to that class of spinning apparatus known as "ring - spinning frames or machines;" and the object of the invention is to equalize the tension on the yarn.

In effecting the object of my invention I make use of a spinning-ring having the base 15 or holder, neck, and race made of separate pieces and sprung together, the race being set upon the neck at an angle of about thirty degrees, and I employ a very light traveler, which is sprung upon the race and has an 20 elevated eye for the yarn and is self-adjusting upon the race, all as I will proceed now more particularly to set forth and finally claim.

In the accompanying drawings, illustrating 25 my invention, in the several figures of which like parts are similarly designated, Figure 1 is a plan view, and Fig. 2 is a vertical section, of the ring. Fig. 3 is a plan view of the base or holder. Fig. 4 is a plan view, and Fig. 5 30 is a side view, of the holder-neck. Fig. 6 is a sectional elevation, omitting, however, the ring-holder, illustrating the application of my invention in spinning. Fig. 7 is a side view, and Fig. 8 an edge view, of the traveler.

35 It has been found to be very desirable that the point of contact of the yarn with the traveler should be at the greatest distance from the center of motion of the traveler, and also that the traveler should have its portion which 40 engages the yarn capable of swinging toward and from the spindle as the centrifugal force of the traveler and tension of the yarn demand. These desirable features are present in my invention. When the ring-race is so 45 constructed as to compel the traveler to stand in an upright position, the traveler must be of such weight at its upper end that the tension of the yarn is not sufficient to overcome the centrifugal force, and hence there follows 50 much spoiled work and much waste of time and material. These objections I avoid in my invention.

In practicing my invention it will be understood that, as in other ring - spinning frames, my ring must be of the right size and 55 the traveler of the proper weight to correspond with the number of the yarn and the desired speed. The holder or base *a* has the notches *b* for the reception of the screws commonly used to secure the rings to the ring-rail, and these notches are made larger than the screw-shanks, in order to admit of the adjustment of the holders to secure as perfect concentricity of the ring and spindle as may be. The holder is made with the upturned 60 lips *c* on its inner edge. The neck *d* of the holder is made, in the preferred form as a concavo-convex ring, of sheet metal, slotted at *d*' *d*'' on its upper and lower edges. By means of this lower slotted edge the neck is 65 adapted to be sprung upon the lips *c* of the holder, and thereby to be securely united to such holder.

The ring-race *e* is made as a flat beveled ring, having in its under face a groove *e*', into 75 which is sprung the upper slotted edge of the holder-neck *d*, whereby the race is united to the holder. The race is arranged upon the holder at about an angle of thirty degrees—that is to say, with an upward and outward 80 flare or slant.

The traveler *f* is constructed of suitable stiff 85 spring metal, with a hook *f*' at one end to engage the ring-race, an upwardly - inclined shank *f*'', overlying the race and which terminates in an eye *f*''' at its highest end to receive the yarn, a curved portion *f*^, working over the upper edge of the race, and a hook *f*^5, engaging the lower face of the upper edge, the hooks *f*' and *f*^5 serving to connect the traveler and race. The traveler may be applied to the race by hooking one end over the edge of the race and springing the other end into place. When the traveler is adjusted upon the ring-race and in operation, its center of 95 vertical motion is at the hook *f*' and the traveler can swing outwardly until the shank *f*'' comes into contact with the ring-race, or it can swing inwardly until the hook *f*^5 comes into contact with the under face of the upper 100 end of the race. In either case the traveler is held to the ring-race by the hooks *f*' and *f*^5 instead of being held by one end only, as in other inventions of mine. As already inti-

mated, the centrifugal force is so great upon a traveler constructed to clasp the ring-race when the ring is made to hold or compel the traveler to swing around in an upright position that it entirely defeats the object aimed at. If the traveler could be swung around upon the ring-race free from all restraint either by the ring-race or the yarn, so far as its outward or inward swinging motion is concerned, the traveler would seek at once a horizontal line in relation to its center of gravity and all of its centrifugal force would be sustained by the hook f' —that is to say, its center of vertical motion—and in this position there would be practically no resistance at the eye f^3 , through which the yarn passes; but when the traveler is held in a position where the shank f^2 is in a perpendicular line the centrifugal force is very great. Between these two points, then, is the proper position to attain success, and in my construction of parts I have demonstrated the correctness of this proposition. The hook f' clasps the inner edge of the ring-race, the hook or lip f^5 prevents the disengagement of the traveler from the race, and the curve f^4 , being described on a circle whose center is the center of vertical motion of the traveler, maintains the same relative position to the outer edge of the ring-race and allows the traveler to swing outwardly and inwardly, as may be required, and prevents it from dropping down or being unhooked from the ring-race.

The shank f^2 is the lever to the eye f^3 . The eye f^3 , through which the thread passes, keeps the thread from slipping down upon the shank into the hook f' , which it would do, were it not for the eye, as soon as the traveler should be thrown outwardly by the centrifugal force—an occurrence that would defeat the object sought to be attained by my invention.

In the art of spinning it is essential that the ring be concentric with the spindle, and this concentricity is no easy matter to preserve, inasmuch as so many forces tend to destroy it—for example, the liability of the spindle to careen out of a perpendicular line, the wear of the lifting-rods of the ring-rail, and the tension of the bands. When there is eccentricity of the ring and spindle in the use of the ordinary ring and traveler, there is a yank upon the yarn at every revolution of the traveler, thereby causing a large number

of breakages and a loss of production and material. With my invention this evil is reduced to a minimum, because the traveler will yield when the ring is out of center. 55

What I claim is—

1. A spinning-ring composed of a holder-base having upturned lips, a ring-race constructed with a groove, and a neck constructed with slits in its lower edge to adapt it to be sprung upon such lips, and thereby secure it and the base, and also constructed with slits in its upper edge, whereby it is adapted to be sprung into the groove of the ring-race to unite them, substantially as described. 60

2. A spinning-ring traveler having a hook at one end, a straight inclined shank terminating at its upper end in a yarn-eye, a curved spring portion whose center of motion is the aforementioned hook, and a stop-hook at the end of said curved portion, substantially as described. 70

3. An inclined ring-race flaring outwardly, 75 in combination with a traveler having a hook to engage the inner and lower end of the race and vibrating thereupon as a lever upon its fulcrum and provided with an elevated yarn-receiving eye which has a to-and-fro motion 80 relatively to the spindle, and also provided with a curved spring portion having a hook to engage the outer and under edge of the ring-race, substantially as described.

4. A traveler constructed with an upwardly-inclined shank, a hook at the lower end of said shank to engage the inner edge of the ring-race, upon which the traveler swings inwardly and outwardly in relation to the spindle as a lever upon its fulcrum, a stop-hook 90 to engage the outer edge of the ring-race, and a yarn-eye at the upper end of said shank, by which the yarn is prevented from slipping down upon the shank when the traveler is thrown outwardly by its centrifugal force, 95 in combination with a ring-race upon which the said traveler can swing inwardly and outwardly in relation to the spindle to an angle of forty-five or more degrees toward the horizontal, substantially as described. 100

In testimony whereof I have hereunto set my hand this 27th day of April, A. D. 1891.

CHARLES H. CHAPMAN.
